CLAIM

The ornamental design for an cabinet for interactive video system, as shown and described.

DESCRIPTION

FIG. 1 is a perspective view of a cabinet for interactive video system, showing our new design;

FIG. 2 is a left side elevational view thereof, the right side being a mirror image;

FIG. 3 is a top plan view thereof;

FIG. 4 is a front elevational view thereof;

FIG. 5 is a rear elevational view thereof.
The bottom of the enclosure is not observable in normal use thereof.

Fig. 1.Fig. 2.Fig. 3.

Fig. 5.
